CARTON

Edward J. Carr, Scarsdale, N. Y.

Application November 13, 1935, Serial No. 49,493

9 Claims. (Cl. 229—27)

This invention relates to cartons and has particular reference to cartons for enclosing and carrying bottles or other containers, although the invention is not limited to that use.

Bottle-carrying cartons in current use are so arranged that the upper ends of the bottles project out of the carton, so that the bottles are not fully protected and the cartons cannot be stacked one upon the other for shipping and storage purposes. Ordinary cartons for containing bottles and other containers are not provided with means whereby they may be conveniently carried and consequently lack the advantages of ready handling and convenience.

In accordance with the present invention a carton is provided which is especially adapted for containing and carrying bottles or other containers in such a way that the bottles or other containers are completely enclosed and accordingly fully protected. The carton is of a geometrical shape, so that it may be readily packed and stacked in the smallest possible space and it is provided with means whereby it may be carried conveniently, either separately or in association with another like carton, both cartons being arranged so that they can be carried in one hand.

More particularly, the invention comprises a carton formed of cardboard or the like, the blank of which consists of an elongated strip which is folded transversely to form front, rear, bottom and top panels. Extending laterally from the front and rear panels and preferably formed integrally therewith are overlapping side panels which are secured together by appropriate tabs. Extending laterally from one of the side panels of the front panel is a flap having struck-out tabs which are folded at right-angles to its surface. When the carton is assembled, this flap is folded inwardly against the inner surface of the rear panel so that the tabs divide the interior of the container into three compartments and serve to separate the bottles therein.

Registering openings are provided in this flap and the engaging rear panel of the carton to serve as a hand hole. Similarly, there is an opening formed in the top panel to serve as a hand hole extending at right-angles to the aforementioned hand hole, so that the hand may be inserted through the top of the closed carton and into the hand hole on the side thereof in order to carry the carton. A tab formed integrally with the top panel is preferably provided with a hand hole which registers with the rear wall hand hole when the tab is inserted within the carton to secure the top panel in closed position. Due to

the location of the hand holes in the rear panel, like cartons may be placed back to back and carried by the same hand which is inserted through the aligned openings in the abutting rear walls of both cartons. The carton blanks may be packed and shipped flat and assembled in the manner described.

In a modified form of the carton of this invention, the flap, instead of being formed integrally with one of the side panels, is formed 10 integrally with the free end of the bottom panel secured to the front panel, and the side and rear panels are lateral extensions of the front panel, thus forming a laterally-extending main strip, the ends of which are secured together by gluing 15 to form a rectangular tube. The flap is folded longitudinally so that its lateral edges overlap and, in this folded condition, it is adapted to be inserted through a slot in the bottom panel of the carton so that it lies against the inner surface 20 of the rear panel with its lateral edges extending at right-angles to divide the interior into three compartments and serving as separators for the bottles or other containers inserted in the carton. Preferably, the free end of this flap is provided 25 with a hand hole adapted to register with the hand hole in the rear panel, so that the weight of the contents of the carton is largely sustained by the inwardly turned flap when the carton is supported by its hand holes. The carton may be 30 packed flat and assembled by inserting the flap in the manner described, together with the usual infolding operation of the bottom and top tabs.

In the second modification, the flap, instead of being inserted within the carton, is folded 35 over the rear panel of the carton with its inwardly turned side edges inserted through companion slots in the rear panel to divide the interior of the carton into three compartments and to serve as bottle separators. Preferably, the 40 free end of this flap is provided with a hand hole adapted to register with the hand hole in the rear panel. In this form the side, front and rear panels are preferably secured together and folded flatwise for packing and shipping. 45

It will be seen that the carton of this invention provides an usually strong and rugged container for packing and carrying relatively heavy bottles or other containers of liquid or the like 50 with security and ease, and when not being carried, the cartons are strong enclosures for the contents, and may be readily handled, stacked and packed.

For a more complete understanding of the in- 55

vention, reference may be had to the accompanying drawings, in which:

Figures 1 and 2 are respectively end and front perspective views of the new carton of this invention, with portions removed;

Fig. 3 is a vertical section through the carton as seen along the line 3—3 of Fig. 2;

Fig. 4 illustrates the carton blank;

Fig. 5 is a perspective view of a modified form 10 of the carton partially assembled;

Fig. 6 is a perspective view of the same in assembled condition with the top open;

Fig. 7 is a vertical section through the carton;

Fig. 8 illustrates the carton blank in disassembled form for shipping and packing;

Fig. 9 illustrates in perspective a second modification of the invention shown partially assembled;

Fig. 10 is a perspective view of the same in assembled condition with the top open; and

Fig. 11 is a vertical section therethrough.

Referring to Fig. 4 of the drawings, which is the blank for the carton illustrated in Figs. 1, 2 and 3, the main strip 20 formed of cardboard 25 or other flexible material, is scored transversely at 21, 22, 23 and 24 to form the top panel 25 with its locking tab 26, the front panel 27, the bottom panel 28, and the rear panel 29. Extending laterally from the front panel 27, are inner side panels 30 and 31, which swing about the respective scored lines 32 and 33. Extending laterally from either side of the rear panel 29 are the outer side panels 34 and 35, which hinge about the respective scored lines 36 and 37.

To the inner ends of the outer side panels 34 and 35 are hinged the respective tabs 38 and 39 and to their outer ends are hinged the respective tabs 40 and 41 which are adapted to be inserted into corresponding slots 40' and 41' 40 formed in the upper ends of the inner side panels 30 and 31, respectively. Formed in top tab 26 is a hand hole 42 shaped like and adapted to register with the hand hole 42' in the upper end of the rear panel 29. Formed in top panel 25 is a similar hand hole 43.

Hinged to the free edge of inner side panel 31 at scored line 44 is a flap 45 having a hand hole 42'' of the same size and adapted to register with hand holes 42 and 42' in the top tab 26 and rear panel 29, respectively. The flap 45 is separated for a part of its length by a slot 46 from inner side panel 31 to which the flap 45 is attached. Transverse slots 47 and 48 permit tabs 49 to be folded about the scored lines 50 at substantially right-angles to the flap 45.

In assembling the carton from the blank illustrated in Fig. 4, the rear panel 29 is folded upwardly about lines 23 and 24 into a position parallel with front panel 27. Then the inner side panels 30 and 31 are folded about lines 32 and 33, respectively, at right-angles to front panel 27 and the flap 45 is folded about line 44 so as to lie flatwise against the inner surface of the rear panel 29 with hand holes 42' and 42'' in registry as is illustrated in Figs. 1, 2 and 3, with the tabs 49 extending across the interior of the carton to divide it into three compartments and serve as separators for the three bottles or other containers inserted within the carton.

Then the tabs 38 and 39 are inserted inwardly to overlie the inner surface of the bottom 39 and hold the separators 50 in extended position, and the tabs 40 and 41 are inserted into corresponding slots 40' and 41' in the upper ends of inner side panels 30 and 31 respectively, these opera-

tions causing outer side panels 34 and 35 to overlie inner side panels 30 and 31 in the manner illustrated in Figs. 1, 2 and 3. The carton may be closed by inserting top tab 26 between the rear panel 29 and the flap 45 so that hand hole 42 registers with hand holes 42' and 42'', as illustrated in Figs. 1, 2 and 3.

The completed carton may be readily carried and handled by inserting the hand into the upper hand hole 43 and out through the side hand hole 42. It will be observed that the parts which are pierced to form the hand holes 42 and 43, namely, rear panel 29, top panel 25, and top tab 26, and which are locked together by the carrying hand, sustain the weight of the contents of the carton, so that there is no danger of collapse of the carton while it is being carried and a rigid, sturdy carrying device is provided.

Also, because the hand holes 42 and 43 are in complementary walls of the finished carton there are no projections which will prevent the carton from being stacked and packed, whether filled or empty, in the smallest possible space. By placing two cartons with their rear panels 29 in engagement, both cartons can be carried by one hand inserted first through the top hand hole 43 of one of them and then through registering hand holes 42 of both of them. The tabs 40 and 41 which are inserted in the slots 40' and 41' serve to lock the outer side panels 34 and 35 against the inner side panels 30 and 31. They may, however, be omitted if desired.

The modified form of the carton illustrated in Figs. 5, 6, 7, and 8 differs from the carton just described in that instead of being secured to one of the side panels the inserted flap is secured to the bottom panel. This arrangement enables the rear panel 51, the front panel 52, and the side panels 54 and 55 to be formed in one lateral strip having its ends secured together by gluing or other fastening means, as is illustrated in Fig. 8. As before, the top panel 56 is an extension of the front panel 52 and is provided with a locking tab 57 provided with a hand hole 58, which is of the same size as and registers with a hand hole 58' in the upper end of the rear panel 51. A hand hole 59, adapted to cooperate with hand holes 58 and 58' is formed in the top panel 56.

The bottom panel 60 is formed as an extension of the front panel 52 and is provided with a flap 61 having its longitudinal edges 62 folded inwardly about lines 63 and its lower edge slotted inwardly at 64 to a point intersecting lines 63. The free end of flap 61 is provided with a hand hole 58'' adapted to register with hand holes 58 and 58' when the carton is in assembled condition. A tab 65 hinged to the lower edge of the rear panel 51 is provided with a transverse slot 66, while the tabs 67 hinged to the bottom edges of the side panels 54 and 55 are provided with notches 68 adapted to register with the slot 66 when the carton is in assembled condition. The upper edges of the side panels 54 and 55 are provided with tabs 69.

In assembling the carton illustrated in Figs. 5 to 8, inclusive, the front and rear panels 52 and 51 respectively, are swung into parallel relation, the tabs 67 folded across the open bottom, and the tab 65 folded across the infolded tabs 66. The sides 62 of the flap 61 are folded over each other as indicated in Fig. 5 so as to reduce its width proportionately and the flap 61 while so folded, is inserted through the slot 66 and cooperating notches 68 so as to lie flatwise against 75

the inner surface of the rear panel 51 with its sides 62 directed at right-angles to divide the interior of the carton into three chambers and serve as separators for bottles or other containers inserted in the carton. In this position, the hand hole 58" in the flap 61 registers with hand holes 58 and 58' in the top tab 57 and rear panel 51, respectively, as is illustrated in Figs. 6 and 7. The tabs 69 on the upper edges of the side panels 54 and 55 are folded inwardly before the top tab 57 is inserted between the rear panel 51 and the flap 61 to close the carton.

It will be observed that as in the form of the invention illustrated in Figs. 1 and 2, the weight of the contents of the carton is borne by the parts which are interlocked by the carrying hand inserted through the registering hand holes 58, 58' and 58" and that this modification has all the advantages of strength, ready handling and carrying and packing of the carton previously described.

The second modified form of the carton illustrated in Figs. 9, 10 and 11 differs from the one illustrated in Figs. 5 to 8, inclusive, in that the flap, instead of being inserted within the carton, extends outside of the carton. As shown in Fig. 9, the main body of the carton, comprising a front panel 70, rear panel 71 and side panels 72, is formed of one strip of cardboard having its ends secured together by glue or the like. The side panels are provided at their opposite ends with upper tabs 73 and the lower tabs 74. Hinged to the bottom edge of the front panel 70 is the bottom panel 75, which is adapted to be folded over the side panel bottom tabs 74. Hinged to the free edge of bottom panel 75 is the flap 76, the side edges of which are folded upwardly at right-angles to form the partition members 77, which, when the flap 76 is folded flatwise against the rear panel 71, are adapted to be inserted through companion slots in the rear panel 71 so as to project into the carton in the manner illustrated in Figs. 10 and 11.

The upper ends 79 of the partition members 77 are folded down temporarily while being inserted within the slot 78 in the rear wall 71. If desired, the free end of the flap 76 may be extended at 80 flush or substantially flush with the upper edge of rear panel 71, and is provided with a hand hole 82' adapted to register with the hand hole 82 of upper end of rear panel 71. The upper end of the front panel 70 is provided with a hinged extension 83 forming the top of the carton and adapted to overlie the upper side wall tabs 73, this top 83 being provided with a tab 84 adapted to be inserted within the carton when the top 83 is folded down. The tab 84 is provided with a hand hole 82" adapted to register with hand holes 82 and 82' when the carton is closed. Likewise, the top 83 is provided with a hand hole 85 through which the hand is inserted so that the fingers extend through the hand hole 82.

This second modification is similar to the other forms in that it is rugged and strong and may be conveniently carried with safety, and may be stacked and packed, having no projections beyond its geometrical surface. Also, in common with the other forms, the weight of the contents of the carton is sustained by parts interlocked by the carrying hand.

It will be observed that in all three forms of the carton of this invention, the blanks of which they are made are generally L-shaped, the two sides or arms of which in each case are folded transversely of their lengths to form the six panels

of the carton with the flaps, 45, 61, or 76, forming the end of one of the sides or arms of the blank.

It will also be observed that not only are the flaps locked to the panel which they overlie by the hand inserted through the registering hand holes in the flap and said panel, but the flap is also held in position against the said panel by the partition-forming tabs on the flap. Thus in the form of Fig. 1, the squared lower edges of the tabs 49 engage the bottom 28 and brace or hold the corresponding flap 45 against panel 29; in the form of Fig. 6 the squared lower edges of the flaps 62 brace or hold the corresponding flap against panel 51, and in the form of Fig. 10 the interlock and friction between the tabs 77 and their slots 78 serve to hold the flap 76 against the panel 71.

While certain preferred embodiments of the invention have been illustrated and described herein, it is to be understood that the invention is not limited thereby but is susceptible of changes in form and detail within its scope.

I claim:

1. In a carton, the combination of side wall 25 and bottom panels flexibly connected together, and a flap hinged on said bottom panel and adapted to lie flatwise upon one of said side panels when the carton is erected, said flap having a length substantially equal to the length of 30 said one panel.

2. In a carton, the combination of side wall and bottom panels flexibly connected together, a flap hinged on said bottom panel and adapted to lie flatwise upon the outer surface of one of 35 said side panels when the carton is erected, and cooperating means on said flap and said last-named side panel for locking said flap in position.

3. In a carton, the combination of side wall and bottom panels flexibly connected together, 40 a flap hinged on said bottom panel and adapted to lie flatwise upon the outer surface of one of said side panels when the carton is erected, and a partition member on said flap adapted to extend into said carton through a slot in said one side 45 panel when the carton is erected.

4. In a carton, the combination of side wall and two bottom panels flexibly connected together, a flap hinged on one of said bottom panels and adapted to be inserted through a slot in said 50 other bottom panel to lie flatwise upon the inner surface of one of said side panels, and projecting means on said flap for holding the latter in said slot.

5. In a carton, the combination of side wall 55 and two bottom panels flexibly connected together, a flap hinged on one of said bottom panels and adapted to be inserted through a slot in said other bottom panel to lie flatwise upon the inner surface of one of said side panels, and a partition 60 member on said flap extending into said carton when erected.

6. In an article-carrying carton, the combination of front, rear, bottom and opposite side panels secured together, a flap overlaying the 65 rear panel and secured to one of said other panels, said rear panel and flap having registering openings adjacent their upper edges forming a hand hole, and a top panel hinged to said front panel and having a hand hole, said two hand holes 70 jointly accommodating the hand for carrying the carton.

7. In an article-carrying carton, the combination of front, rear, bottom and opposite side panels secured together, a flap overlaying the 75

rear panel and secured to one of said other panels, said rear panel and flap having registering openings adjacent their upper edges forming a hand hole, tabs on opposite sides of said flap dividing 5 said carton into three compartments, and a top panel hinged to said front panel and having a hand hole, said two hand holes jointly accommodating the hand for conveying the carton.

8. In an article-carrying carton, the combination 10 of front, rear and opposite side panels secured together, a bottom therefor, and a top hinged to the upper edge of one of said panels, said top having a hand hole and said rear wall having a hand hole adjacent its upper edge 15 aligned with the top hand hole, whereby two cartons may be placed back to back and carried

by one hand thrust through the top hand hole of one of said cartons and the registering rear hand holes of both cartons.

9. A carton formed of a substantially L-shaped blank, both arms of which are folded transversely 5 to form the six panels of a rectangular carton and a flap, said flap being hinged to the edge of one of said panels and being adapted to be folded flatwise upon another panel and having substantially the size of said other panel, and at least 10 one partition member formed of an infolded portion of said flap for holding said flap in said flatwise position and for dividing said carton into compartments when erected.

15

EDWARD J. CARR.
